UNITED STATES PATENT OFFICE.

LOUIS V. SHAW, OF WAUWATOSA, WISCONSIN.

PORTABLE MECHANICAL EXERCISING MACHINE.

Application filed March 22, 1928. Serial No. 263,650.

This invention pertains to mechanical exercising machines of the type adapted to mechanically vibrate any desired portion of the body.

5 Heretofore machines of this character have been exceedingly heavy and cumbersome in design, which rendered them costly and more or less stationary. It is therefore the primary object of the present invention to provide a mechanical exercising machine, having all of the advantages and desirable features of the present machines on the market, and which is comparatively light, compact, and inexpensive, whereby the same is readily 10 portable, may be quickly attached to any desired support, and is within the reach of people of moderate financial circumstances.

Incidental to the foregoing, a further object is to provide a compact structure, where- 20 in the motor and actuated mechanism is housed within a unitary casing.

Another object is to provide novel means for detachably clamping the machine to any suitable support, such as a door jamb, window casing, bath tub, or other convenient support.

Another object is to provide a machine which may be quickly detached from its clamping means to render the same more compact in shipping.

A still further object is to provide novel means for attaching the various appurte- 30 nances, whereby accidental detachment is prevented during operation.

35 With the above and other objects in view, which will appear as the description pro- ceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

40 In the accompanying drawings is illus- trated one complete example of the physical embodiment of the present invention con- structed according to the best mode so far devised for the practical application of the principles thereof.

45 Figure 1 is an elevational view of a machine constructed in accordance with the present invention, illustrating the same attached to a door jamb, or similar form of vertical support.

50 Figure 2 is a longitudinal, sectional view

taken through the motor and mechanism housing, and the supporting bracket, the same being indicated on the line 2—2 of Figure 3.

Figure 3 is a transverse section taken on the line 3—3 of Figure 2.

Figure 4 is a transverse section through the motor housing, illustrating the method of supporting the motor.

Figure 5 is a detailed view of one of the 65 appurtenances used in connection with the present machine.

Figure 6 is a detailed section taken on the line 6—6 of Figure 5, and

Figure 7 is a detailed view of the clamping 70 bracket employed.

Referring now more particularly to the accompanying drawings, the numeral 1 designates a housing open at its ends and provided with an intermediate partition 2 having a central bearing 3. Removably secured to the ends of the housing 1 by means of bolts 4, or other suitable means, are the closure plates 5, each provided with inwardly projecting, central bosses 6, recessed for the reception of anti-friction bearings 7.

The forward chamber 8, formed in the housing 1, is provided with radially spaced, longitudinal ribs 9, which engage and support the field 10 of a conventional type of electric motor. The armature shaft 11 extends throughout entire length of the housing 1 and is journaled in the ball races 7, and the central bearing 3 in the partition 2. Thus it will be seen that the armature shaft 90 is supported at three points and is held against end thrust by the anti-frictional bearings 7.

95 Mounted on the armature shaft 11 within the rear compartment 12 is a worm 13 which meshes with the worm wheel 14 mounted on the transverse shaft 15, which shaft is journaled in the anti-friction bearings 16 mounted in the bosses 17 formed in the housing 1. The bosses 17 are recessed at the exterior of 100 the casing for the reception of the pitmen 18 mounted on the outer ends of the transverse shaft 14. The pitmen 18 carry the crank pins 19, to which are secured the connecting links 20, that in turn are secured to the plungers 21, slidably journaled in the bearings 22 formed on opposite sides of the housing 1.

105 In order to render the present machine more compact for shipping, it is proposed to form the clamping means separate and distinct from the housing for the motor and actuated mechanism. The supporting brack- 110

et 22' is therefore provided, which has a face 23 adapted to abut any vertical support. Formed in the bracket 22 is a recessed boss 24 for the reception of a tie-rod 25, which rod is detachably secured in the boss by a tapered pin 26.

For the purpose of rigidly attaching the motor housing to the supporting bracket, the former is provided with a pair of spaced longitudinal legs 27 having slots 28 formed therein for the reception of the lugs 29 carried by the nuts 30. In turn the nuts 30 are threaded on the thumb screws 31 which are carried by the bosses 32 formed on opposite sides of the bracket.

For the purpose of detachably clamping the supporting bracket 22 to a convenient support, a clamping bracket 33 is adjustable mounted on the tie-rod 25, and may be locked in adjusted position by a pin 34 adapted to register with the spaced openings 34', provided in the tie-rod. The bracket 33 is provided with a pair of offset arms 35, each of which carries a thumb screw 36 adapted to clampingly engage a support, which, in the present instance, is illustrated as a door casing 37.

From the foregoing description it will be readily appreciated that a very simple and compact structure has been provided, which is exceedingly light and readily portable, the portability being facilitated by a handle 38 secured to the housing 1. It will also be seen that the motor and actuated parts are readily accessible for inspection or lubrication when necessary. Particular attention is also directed to the fact that the novel clamping means provided enables the machine to be attached to a support at a height most desirable and convenient to the operator, which feature is lacking in the present types of machines on the market. It will also be understood that the particular structure of clamping means provided readily lends itself for rigid attachment to any form of stationary support, such as a window sill, door casing, bath tub, or the like, as the bracket 33 may be quickly adjusted on the tie-rod 25, and clamping action thereafter obtained through the thumb screws 36.

In the use of the device various appurtenances may be employed, which appurtenances essentially include a flexible belt or strap 39, the ends of which are attached to the reciprocating plungers 21. Heretofore it has been common practise to provide loops in the ends of the belt, and adapted to be slipped over arms or lugs formed on the ends of the plungers. In practise it has been found that the belts attached in this manner become accidentally disengaged from the plungers during the operation of the machine. The present invention therefore aims to overcome this objectionable feature by providing the outer ends of the plungers 21 with hooks 40, the

mouths of which are restricted at 41. These hooks receive the pintles 42 carried by the loops 43 secured to the ends of the belt 39, the pintles 42 having a flattened face 42', as best shown in Figure 5, which permits them to be inserted past the restricted mouths of the hooks 40 and thereafter turned to lock in operative position.

To eliminate a multiplicity of appurtenances it is also proposed to attach grips 44 to the belt 39, which permits the use of the same for exercises not requiring the belt.

In operation it will be readily seen that simultaneous and alternate reciprocatory motion is transmitted to the plungers 21 by means of the worm and worm wheel drive between the motor and transverse shaft 15, which in turn drives the pitmen 18. In practice the ends of the belt are secured to the hooks 40, which will cause an oscillatory movement of the belt to cause vibration to the portions of the body over which the belt is passed. The advantages and benefits derived from the foregoing exercise are so well-known as to require no further emphasis here.

While the motor and actuated parts are compactly housed, it will be noted that provision is made for ventilating the front chamber 8 to cool the motor. This is accomplished by the openings 45 and 46 formed in the front end closure 5 and motor housing 1, respectively. The rear housing, which contains the driving mechanism, is completely closed, thus affording opportunity to adequately grease or lubricate the driving transmission.

I claim:

1. A portable exercising machine comprising a unitary housing provided with a central partition and open at its ends, closure plates secured to the ends of said housing, a motor mounted within said housing and having an armature shaft journaled in said partition and end closures, said housing being provided with openings to ventilate said motor chamber, a transverse shaft journaled in said housing and having its ends projecting therefrom, a worm gear drive between said armature shaft and transverse shaft, 105 cranks mounted on the projecting end of said transverse shaft, plungers slidably journaled upon opposite sides of said casing, links connecting said cranks and plungers for reciprocating said plungers, hooks formed on the 110 ends of said plungers for the reception of exercising appurtenances, said hooks having restricted mouths for locking said appurtenances when in operative position.

2. A portable exercising machine comprising a unitary housing provided with a central partition and open at its ends, closure plates secured to the ends of said housing a motor mounted within said housing and having an armature shaft journaled in said par- 115 120 125 130

tion and end closures, a transverse shaft journaled in the housing and having its ends projecting therefrom, means forming operative connection between the armature shaft and transverse shaft, cranks mounted on the projecting ends of said transverse shaft, plungers slidably journaled upon opposite sides of said casing, links connecting said cranks and plungers for reciprocating the plungers, hooks formed on the ends of said plungers for the reception of exercising appurtenances.

3. An exercising device including a hous-

ing, slotted supporting legs therefor, a bracket, bosses carried by the bracket, thumb screws mounted in said bosses, nuts on the thumb screws and laterally projecting lugs on the nuts for engaging the slotted legs to retain the housing against movement relative the bracket.

In testimony that I claim the foregoing I have hereunto set my hand at Milwaukee, in the county of Milwaukee and State of Wisconsin.

LOUIS V. SHAW.
